CLAIM

The new, original, and ornamental design for a tamper evident lid for a container, as shown and described.

DESCRIPTION

FIG. 1 is a top, left, and front perspective view of a tamper evident lid for a container;

FIG. 2 is a top plan view thereof;

FIG. 3 is a bottom plan view thereof;

FIG. 4 is a top, right, and front perspective view thereof when in a closed position;

FIG. 5 is a right side elevational view thereof;

FIG. 6 is a rear elevational view thereof; and,

FIG. 7 is a front elevational view thereof.

The broken lines in the drawings depict environmental subject matter only and form no part of the claimed design.
